METHOD OF FORMING A HARNESS CORD END TERMINAL

Robert B. Hayden, Newtonville, Mass.

Application December 15, 1955, Serial No. 555,214

1 Claim. (Cl. 29—517)

This invention relates to harness cords for looms, and more particularly to a method of forming a terminal for anchoring one end of the harness cord to the loom frame.

The principal object of this invention is to provide a harness cord having a terminal which is not only of simple construction and inexpensive to make, but which is also so firmly anchored to the cord that it cannot loosen under repeated use.

Another object of this invention is to provide a harness cord connector which is adapted to be brought into direct engagement with the metal cable core of the cord in such a manner that the metal of the connector is caused to flow around the individual strands of the core.

A further object is to provide a harness cord having a terminal at one end comprising a connector or ferrule having an eyebolt or hook, the shank of the eyebolt or hook being so secured within the connector that it cannot loosen under repeated use.

Another object is to provide a connector for harness cords manufactured from solid rod stock having a first bore to receive the end of the cord, a second bore to receive the core of the cord, and a third bore to receive the shank of an eyebolt or hook, the second bore being of progressively decreasing cross section so that the core of the cord may be held under a compression which gradually increases in the direction of said third bore.

Other objects and many of the attendant advantages of this invention will be readily appreciated as the same becomes better understood by reference to the following detailed description when considered in connection with the accompanying drawings, wherein:

Fig. 1 is an enlarged elevation showing the end of a harness cord preparatory to being provided with the improved terminal of the present invention;

Fig. 2 is an enlarged longitudinal section of the ferrule or connector element of the terminal prior to being secured to the cord;

Fig. 3 is an enlarged longitudinal section showing the end of the cord of Fig. 1 secured to the connector of Fig. 2;

Fig. 4 is an enlarged elevation of an eyebolt to be added to the assembly of Fig. 3;

Fig. 5 is an enlarged longitudinal section showing the completed terminal;

Fig. 6 is a longitudinal section through a modified form of the connector element;

Fig. 7 is an enlarged side elevation of a modified form of eyebolt; and

Fig. 8 is a longitudinal section of a completed terminal embodying the modified connector element and eyebolt of Figs. 6 and 7 respectively;

Fig. 9 is an enlarged longitudinal section showing the terminal completed in one operation.

Referring now to Fig. 1, there is shown the end of a conventional harness or dobby cord which includes a braided external sheath 2 of organic material, e.g., textile fibres, surrounding a steel wire or cable core 4. The

2

sheath is stripped at the end to expose the wire core, as shown. Although only one end is shown, it is to be understood that both ends of the harness cord will be attached to identical terminals constructed according to the present invention.

According to the preferred form of the invention the harness cord is first provided with a ferrule or connector 6 shaped as indicated in Fig. 2. Ferrule 6 is manufactured from conventional solid rod stock and is provided with three bores 8, 10 and 12 respectively. In practice I prefer to use a harness cord whose sheath 2 has an outside diameter of approximately .219" and whose core 4 has an outside diameter of about .063". For a cord of the foregoing dimensions I have found that a most suitable ferrule or connector can be manufactured from a section of rod stock measuring 1 $\frac{1}{16}$ " in length and $\frac{5}{16}$ " in diameter. Bores 8 and 10 are formed in the rod stock to accommodate the sheath and core portions respectively of the cord. For a cord of the above dimensions it has been found that bore 8 should measure about .261" and should extend through a distance of about $\frac{5}{16}$ ". Bore 10 extends through a distance of about $\frac{1}{2}$ " and has a constant diameter of about .076" for about one-half of its length extending away from bore 12 toward bore 8. The left hand half of bore 10 tapers to about .146" or double the diameter of the right hand half. The left end of bore 10 is reamed as at 16 to present a smooth bell-mouth surface to the wire core. Bore 12 has an initial diameter of about .166", sufficiently large to accommodate the stem or shank 18 of eyebolt 20 even after the cord has been anchored in the ferrule, as explained hereinafter.

In assembling the terminal the cord is inserted in the ferrule as shown in Fig. 3. Thereafter the ferrule is placed in a conventional rotary swaging machine or a hammering machine, as preferred, which reduces the diameter of the ferrule uniformly throughout its length. For a ferrule having the specific construction outlined above it is preferred to reduce the exterior diameter of the ferrule by about .031". The dash lines 22 in Fig. 3 represent the original diameter and length of the ferrule before swaging or hammering operation.

During the swaging or hammering operation the metal of the ferrule is caused to flow into intimate and close contact with the filaments of the core except for a small section adjacent the end of the sheath corresponding to the maximum taper-reamed area of bore 10. Due to the fact that the left hand half of bore 10 originally had a varying diameter and the ferrule was subjected to a uniform deformation throughout its length, the compression to which core of the cable is subjected increases gradually in the direction of bore 12 for about half the length of bore 10. The compression is substantially constant for the right hand half of bore 10. Since the contact between the ferrule and the core of the cable decreases progressively in the direction of bore 8, there is no harmful pinching of the core adjacent the end 14 of sheath 2 and the work load is spread gradually over the compressed core. The reduction in diameter of the ferrule is sufficient to bring the wall of bore 8 into tight engagement with the sheath, although the reduction in diameter of the sheath is barely perceptible to the naked eye.

After the cord has been secured to the ferrule, the shank 18 of an eyebolt 20 is inserted in bore 12. The length of shank 18 of the eyebolt 20 and also of shank 42 of eyebolt 44, is exaggerated in the drawings to better illustrate the shape of the end of the eyebolt. In practice the shank is relatively short so that the looped end of the eyebolt will be positioned close to the end of the ferrule when the eyebolt is attached thereto.

Preferably shank 20 measures about .130", slightly smaller than bore 12 after it has been reduced in size.

A couple of small indents 24 measuring about $\frac{3}{32}$ " wide and .015" deep are provided in shank 20 as a means to lock the ferrule with the eyebolt. Once the eyebolt has been inserted, the assembly is placed in a punch press which crimps the ends of the ferrule, as shown at 26 and 28. This causes the left hand end of the ferrule to make a very tight engagement with the sheath and causes the right hand end to make firm engagement with the eyebolt.

Due to the fact that the eyebolt extends within the ferrule and is in direct engagement with it, the eyebolt will not pull out under repeated and continuous use. This direct metal to metal engagement is responsible for the great strength of the connection between the eyebolt and ferrule.

With respect to said preferred form of the invention, it is to be understood that bore 10 may be of varying diameter throughout its entire length instead of only half without departing from the spirit of the invention.

A modified form of the invention is illustrated in Figs. 6, 7 and 8. In this form of the invention a ferrule 30 is provided having three bores 32, 34 and 36 as in the preferred embodiment. However, in the modified embodiment the central bore 34 is of substantially the same diameter throughout its length except for a short section 38 adjacent bore 32 which is reamed as shown to provide a smooth bell-mouth surface to the wire core. The diameter of bore 34 is substantially the same as the diameter of the right half of bore 10 illustrated in Fig. 2. Bore 36 is slightly larger than bore 12 of the preferred embodiment in order to accommodate the enlarged shoulder 40 of the shank 42 of an eyebolt 44. Eyebolt 44 differs from eyebolt 20 only in the shape of the end of its shank. It is to be understood that eyebolt 44 may be provided with a pair of outwardly extending protuberances in place of continuing shoulder 40, thereby to provide greater assurance against rotation of the shank relative to the ferrule.

In assembling the modified form of the invention, the end of the harness cord is inserted into the left hand end of ferrule 30. Thereafter the ferrule is inserted into a swaging machine having tapered dies so as to cause the right hand end of the ferrule to be subjected to a greater compression than the left hand end of the ferrule.

In Fig. 8 the dash lines 48 indicate the original diameter of the ferrule before swaging. In this latter embodiment the core of the cord, due to the fact that the swaging has been accomplished by tapered dies, is subjected to a gradually increasing compression in the direction of bore 36. Only a minor portion of the core adjacent the end of the sheath remains out of engagement with the ferrule.

After the cord has been secured to the ferrule, the eyebolt 44 is inserted in bore 36. Thereafter the assembly is placed in a punch press and crimped as at 50 and 52 to place the ferrule in firm engagement with the cord and the shank of the eyebolt. The direct metal to metal engagement between the ferrule and the eyebolt provides a connection so secure that the eyebolt will not pull out of the ferrule during repeated use. The embodiment of Fig. 5 may also be made in one operation as explained hereinafter in connection with Fig. 9. This method of assembling the terminal has the advantage of eliminating the punch press operation previously described to crimp the ends of the ferrule. In this case cord 2 is inserted in the left hand end of ferrule 6, shank 18 of the eyebolt is inserted in the right hand end of the ferrule, and the resultant loose assembly is placed in an open die rotary swager or a hammering machine. By means of the swager or hammering machine the diameter of the ferrule is reduced uniformly, except at 26a where the ferrule is reduced to a greater extent in a taper so as to engage the sheath very tightly. As before the metal of the ferrule is caused to flow into the interstices of the wire core. The metal also flows into and fills indents 24, making a

solid engagement with shank 18 of the eyebolt 20. The dashed lines 22a represent the original diameter and length of the ferrule prior to being reduced in the swager or hammering machine. It is to be understood that the terminal of Fig. 8 may be assembled and shaped in a single operation in the same manner. Thus, cord 2 and shank 42 of eyebolt 44 are inserted in the left and right hand ends respectively of ferrule 30, and the resultant assembly is placed in an open die rotary swager or a hammering machine and reduced variably so as to subject the core to a gradually increasing compression in the direction of bore 36. The ferrule will be tapered as shown when the reduction is completed. The rotary swager or hammering machine will simultaneously effect greater reduction at the ends of the ferrule so that the ferrule will be compressed tightly about the sheath and eyebolt as at 50 and 52 in Fig. 8.

It is to be understood that although the embodiment of Figs. 5, 8 and 9 have been described as embodying a cord, ferrule and eyebolt of specific sizes, the dimensions thereof may be varied according to the specific requirements without departing from the spirit of the invention. It is also to be understood that the loop of the eyebolt may be open so as to form an open hook and that the term "eyebolt" as used in the claim is to be construed as including the latter form of loop. Harness cords having terminals constructed according to the present invention are exceptionally strong and have the advantages of being simple to construct and cheap to manufacture. In practice neither eyebolt nor wire core will break or pull out of the ferrule. Failure of the harness cord therefore will be due ultimately to wearing out of the sheath over pulley. Because the invention can be carried out by means of a rotary swaging machine, as well as a conventional hammering machine, the harness cords may be assembled very rapidly and with substantial standardization of quality. The ferrule, being manufactured from rod stock rather than sheet material as has been previously accomplished, provides good strength and permits the manufacture of harness cord terminals that are small and compact.

Obviously many modifications and variations of the present invention are possible in the light of the above teachings. Therefore, it is to be understood that the invention is not limited in its application to the details of construction and arrangement of parts specifically described or illustrated, and that within the scope of the appended claim it may be practised otherwise than as specifically described or illustrated.

50 I claim:

The method of forming an end terminal for a harness cord comprising the steps of providing a solid metal rod of circular cross-section, making a first axially-extending bore of circular cross-section in said rod at one end 55 thereof, making a second circular tapered bore in said rod continuous with said first bore, making a third axial bore in the opposite end of said rod of larger diameter than said second bore, providing a harness cord comprising a flexible wire core encased in a sheath of organic material, removing some of the sheath from one 60 end of the cord to lay bare the end portion of said wire core, inserting said end of the cord into said rod so that the bare end of the core resides in said second bore and the end of the sheath resides in said first bore, impacting said rod uniformly about its circumference to 65 make a tight connection with the bare end of said core substantially throughout the entire length of said bare end, providing an eyebolt for securing said harness cord to a loom, inserting the stem of said eyebolt into said third bore, and crimping said rod in the region of said third bore to place it in tight fixed engagement with said stem.
